UNITED STATES PATENT OFFICE.

GEORGE T. PILLINGS, OF CINCINNATI, OHIO, ASSIGNOR TO JOHN G. BECK,
OF BALTIMORE, MARYLAND.

CAN-SOLDERING MACHINE.

SPECIFICATION forming part of Letters Patent No. 569,765, dated October 20, 1896.

Application filed February 20, 1896. Serial No. 580,065. (No model.)

To all whom it may concern:

Be it known that I, GEORGE T. PILLINGS, a citizen of the United States, residing at Cincinnati, in the county of Hamilton and State 5 of Ohio, have invented certain new and useful Improvements in Can-Soldering Machines, of which the following is a specification.

My invention relates to machines for soldering the longitudinal seams of cylindrical or 10 other cans or vessels, and has for its object more especially to provide a soldering clamp or "horn" having gages so arranged that the can or vessel blank will be trued, and the seam of the completed can or vessel, when delivered from the machine, will have a uniform 15 lap throughout.

The invention is designed to be used either by a single operator or two or more operators. In the latter case a revolving table is employed, in which the device or a series of the 20 said devices are arranged upon the table.

My said invention consists in the novel construction, arrangement, and combination of the various parts, all of which I will now proceed to point out and describe, reference being had to the accompanying drawings, in 25 which—

Figure 1 is a side elevation of a portion of the machine sufficient to illustrate my invention. Fig. 2 is a plan view of the same. Fig. 3 is a front elevation, and Figs. 4, 5, and 6 are 30 sectional views taken on the line $x-x$ of Fig. 1, the parts being shown in different positions to illustrate the manner in which the machine 35 is used.

In the said drawings, 1 indicates the bed-plate of the device, bolted or otherwise attached to a suitable table 2, as shown. Pivotedly mounted in suitable bearings 3 on said 40 bed-plate is a lever 4, having interposed between its rear end and the table 2 a strong spring 5, adapted to normally force said rear end upward. Also connected to said rear end of the lever 4 is a suitable connection 6, passing down through an aperture in the table and connected at its lower end to a foot-treadle 7 of any suitable construction, the two 45 adapted to depress the rear end of the lever 4 against the tension of the spring 5. Also

mounted on the table 2 is a stop 8, against 50 which the rear end of the lever 4 will strike when depressed, thus limiting the downward movement of said lever.

Projecting horizontally from the front side of the bed-plate 1 and beyond the edge of the 55 table is what I term a "horn" 9, of a length substantially equal to that of the can or vessel to be soldered, having its upper face of suitable contour to form a bed or support for the can edges. Mounted in vertical apertures 10 in said horn, and normally projecting somewhat above the top surface thereof, are a series of depressible gages 11. These gages are each provided with a collar 12, formed integral therewith and adapted to engage 60 with a shoulder 13 in its aperture 10. The lower end of said aperture is screw-threaded, as shown, to receive the screw-threaded nut 14, the latter being centrally apertured to receive the lower end of its gage 65 11. Interposed between the collar 12 on the gage 11 and the upper end of the nut 14 is a spiral spring 15, the function of which is to press the gage upward, so that the collar 12 thereon will normally abut against the shoulder 13 in the aperture 10. When in this position, the upper end of the gage 11 will project above the upper face of the horn 9.

The front end of the lever 4 normally lies 70 parallel with the horn 9 and somewhat to one side of the longitudinal center thereof, and has adjustably attached to it a clamping-knife 16, adapted to contact with the depressible gages 11 in said horn. By making this clamping-knife adjustable on the lever 4 the same 75 80 may be adjusted to fit accurately against the upper surface of the horn. As shown, the knife 16 is connected to the lever 4 by a central screw or bolt 16^a, which renders it self-adjusting on the horn 9. Pivoted to said lever 4 a little in front of its pivotal point and on the same side thereof as the clamping-knife 16 is an additional gage 17, adapted, 85 when in its lowermost position, to lie upon the upper surface of the horn 9 parallel with the clamping-knife 16. This gage is provided 90 at its front end with a U-shaped extension 18, adapted to embrace the front end of the 95

lever 4, but cut out sufficiently to permit said lever and its attached clamping-knife to be raised free from the horn 9 and the depressible gages 11 before the two will contact. This 5 U-shaped extension is intended to raise the pivoted gage 17 from the surface of the horn 9 at the instant the clamping-knife 16 leaves the depressible gages 11 and also to act as a guide for the front end of the pivoted gage 10 to prevent any possible lateral movement. Also fixed to the inner side of said gage 17 near its pivotal point is a downwardly-projecting lip 19, adapted to lie in an opening 20 in the horn 9 when said gage is in its lower-most position.

The operation of my invention is as follows: When the side seam of a can is to be soldered, the operator, located in front of the table, will raise the front end of the lever 4 and its 20 attached clamping-knife 16 and gage 17 by depressing the treadle 7, so that the clamping-knife will be raised clear of the depressible gages 11 and gage 17 clear of the horn 9, the stop 8 permitting this much movement to 25 the lever, but preferably no more. Now with the previously-curved can body or blank held in both hands the operator passes the underlap edge thereof with his right hand over the top surface of the horn 9 until the 30 longitudinal edge of the blank comes in contact with the depressible gages 11, as shown in Fig. 4. The operator then passes the overlap edge of the blank between the raised clamping-knife 16 and the depressible gages 35 11 until its longitudinal edge abuts against the inner edge of the pivoted gage 17, thus overlapping the underlap edge of the blank, it being understood that there is left between the adjacent faces of the clamping-knife 16 and the pivoted gage 17 a small space about 40 equal to the required lap. When the two edges of the blank are in this position, the rear ends of the lap should be against the lip or end gage 19. Now by releasing the treadle 45 the clamping-knife 16 by the spring 5 will be forcibly pressed upon and clamp the two edges of the blank in their adjusted overlapped position ready for soldering, the depressible gages 11 being at the same time 50 forced by the pressure down into the horn 9. The pivoted gage 17 is now thrown back and the overlapped edge of the blank is exposed ready for soldering.

While in the above description I have confined myself to the description of a single clamping device fixed to any suitable table and adapted for manipulation by one operator, I wish it to be understood that I do not confine myself to such construction, as I may, 55 if desired, employ a rotating table having a series of clamping devices thereon, around which may be located two or more operators, some engaged in clamping the blanks and others in soldering the same. Thus, for instance, with a rotating table having, say, eight

clamping devices thereon one operator may clamp the blanks while another operator on the other side of the table will solder the same as the table is rotated, the first-named operator removing the soldered blanks as the clamping devices come back to him in the rotation of the table.

It will be apparent that various changes in the mechanical details of construction and arrangement may be made without departing 75 from the spirit of my invention. Thus, for instance, instead of the depressible spring-pin gages in the horn I may use a single depressible gage long enough to true the edge of the blank, said gage being seated in a slot 80 in the horn and sustained by one or more springs.

Therefore, without limiting myself to the precise form shown and described, I claim—

1. In a can-soldering machine, the combination with a blank-receiving horn, of one or more depressible gages therein adapted to gage and true the underlap edge of the blank, a movable gage for gaging and truing the overlap edge of said blank, and means for retaining said adjusted edges in position for soldering after being gaged and trued, substantially as shown and described.

2. In a can-soldering machine, the combination with a blank-receiving horn, of one or 95 more depressible gages therein adapted to gage and true the underlap edge of the blank, a pivoted gage for gaging and truing the overlap edge of said blank, and a pivoted spring-pressed lever carrying a clamping-knife 100 adapted to retain said adjusted edges in position for soldering after being gaged and trued, substantially as shown and described.

3. In a can-soldering machine, the combination with a blank-receiving horn, of one or 105 more depressible gages therein adapted to gage and true the underlap edge of the blank, a pivoted gage for gaging and truing the overlap edge of said blank, a pivoted spring-pressed lever carrying a clamping-knife 110 adapted to retain said adjusted edges in position for soldering after being gaged and trued, and means for raising said lever and clamping-knife against the tension of said spring while the edges of the blank are being 115 adjusted, substantially as shown and described.

4. In a can-soldering machine, the combination with a blank-receiving horn, a series of depressible gages therein adapted to gage 120 and true the underlap edge of the blank, and means for retaining the adjusted edges of the blank in position to be soldered, of a pivoted gage adapted to gage and true the overlap edge of the blank and to be then turned back 125 out of the way to permit free access to said overlap edge for the purpose of soldering the same, substantially as shown and described.

5. In a can-soldering machine, the combination with a blank-receiving horn, one or 130

more depressible gages therein adapted to
gage and true the underlap edge of the blank,
and a pivoted lever carrying a clamping-knife
for retaining the adjusted edges of the blank
5 in position for soldering, of a gage pivoted to
the lever for gaging and truing the overlap
edge of the blank, and an auxiliary gage car-
ried by said pivoted gage for gaging and tru-

ing the ends of the blank, substantially as
shown and described.

In testimony whereof I affix my signature
in presence of two witnesses.
